UNITED STATES PATENT OFFICE

JOSEPH SASSANO, OF NEW YORK, N. Y.

FLOOR WAXING AND POLISHING MACHINE

Application filed May 17, 1927. Serial No. 192,058.

This invention relates to floor waxing and polishing machines and has for one of its objects to provide a machine of this character which will be simple in construction, 5 comparatively inexpensive to manufacture and more efficient in use than those which have been heretofore proposed.

A further object of the invention is to provide a machine of the class described in 10 which the driving motor is housed in an isolated chamber to the end that it may be protected from the dust and wax particles which are necessarily thrown off by the rotating polishing brush.

15 A still further object of the invention is to provide for the efficient ventilation and cooling of the driving motor to the end that the heat generated thereby will be dissipated without being transmitted to the frame of the 20 machine thereby eliminating to a large extent, melting of the wax particles thrown off by the brush, which in the prior machines, has resulted in the coating of the machine with a layer of wax which has necessitated a 25 cleaning of the machine every time it is used.

With the above and other objects in view which will appear as the description proceeds, the invention consists in the novel details of construction and combinations of 30 parts more fully hereinafter described and particularly pointed out in the appended claims.

Referring to the accompanying drawings forming a part of this specification in which 35 like reference characters designate like parts in all the views:

Figure 1 is a side elevational view of a waxing and polishing machine constructed in accordance with the present invention;

40 Fig. 2 is a vertical sectional elevational view on an enlarged scale taken approximately on the plane indicated by the line 2—2 of Fig. 3, looking in the direction of the arrows;

45 Fig. 3 is a horizontal sectional view taken approximately on the plane indicated by the line 3—3 of Fig. 2, looking down, certain of the parts being shown in elevation;

50 Fig. 4 is a vertical cross sectional view taken approximately on the plane indicated

by the line 4—4 of Fig. 3, looking in the direction of the arrows;

Fig. 5 is a top plan view of the machine as shown in Fig. 1;

Figs. 6 and 7 are respectively side elevational and end elevational views showing in detail, the motor mounting; and,

55 Fig. 8 is a longitudinal vertical sectional view through the frame or housing with the motor and brush omitted and taken approximately on the plane indicated by the line 8—8 of Fig. 3.

Referring to the said drawings the numeral 10 indicates generally the housing of the machine which comprises a central main section 11 and the laterally offset portions 12 and 13. The side walls of the said sections 12 and 13 extend forwardly and have mounted therein, a shaft 14 which is preferably retained in place by the bolts or screws 15, as 60 will be readily understood. The ends of the said shaft are reduced as at 16 to receive the antifriction bearings 17 upon the outer races of which is mounted the drum of the brush 18 which is provided with suitable tufts of bristles 19, as will be clear from 65 Figs. 1, 2 and 3.

70 As will be noticed from Figs. 3 and 5, the brush 18 at one end, extends close to the wall of the offset portion 12 while at its 80 other end, it is provided with a pulley 20 around which passes the belt 21 for driving the brush.

The housing 10 is provided with a transversely extending partition wall 22, see Figs. 85 2, 3, 4 and 8, which divides the said housing into a brush chamber 23 and a motor chamber 24. The said partition wall 22 is imperforate except for the opening 25 provided within the offset portion 13 and 90 through which the driving belt 21 is adapted to pass, as will be readily understood from the drawings.

A motor 26 is mounted in the motor chamber 24 in any suitable manner but preferably 95 by means of the pendulous suspension shown in detail in Figs. 3, 6 and 7. This suspension as will be clear from the said figures, comprises the reversely positioned U-shaped strap members 27 and 28 carried respectively 100

by the main portion 11 of the housing 10 and the motor 26, with their ears 29 and 30 pivotally connected by means of the rod or shaft 31 extending therethrough. An L-shaped 5 spring member 32 is secured at one end to the U-shaped strap member 27 and its other end bears against the motor casing, as clearly shown in Fig. 7, tending to swing the motor in a counter-clockwise direction about its pivot 31, as seen in Fig. 7, and serving to maintain the belt 21 in driving relation to the pulley 20. The driving shaft 34 of the motor is provided with a pulley 35 about which the belt 21 passes, as will be readily 10 understood from Figs. 2 and 3.

As above stated, the partition wall 22 is imperforate except for the opening 25 so that the motor chamber 24 is substantially completely isolated from the brush chamber 23. It therefore follows that the said chamber 24 and the motor 26 are completely protected from dust and wax particles thrown off by the brush 18, except for the said opening 25. In order to prevent such foreign 20 matter from finding its way through this opening, there is provided a longitudinally extending wall 36 running forwardly from the transverse partition 22 in close proximity to the lower end of the brush 18, as viewed 25 in Fig. 3. This said wall 36 is cut away as at 37 to closely follow the contour of the drum of the brush 18, (see Figs. 2, 3 and 8,) and it therefore follows that dust and wax particles will be prevented by the 30 said partition wall from finding their way through the belt opening 25 in the transverse wall 22 so that the motor will be completely protected from such foreign matter.

In prior machines of this character it has 40 been found that the heat necessarily generated by the operation of the electric driving motor has been so great that the wax particles thrown off by the revolving brush have been melted upon the various parts of the 45 machine and fused into a solid coating covering such parts. It has, therefore been necessary with the prior machines to scrape off or otherwise remove this wax coating each time the machine is used, which operation has been exceedingly difficult and disagreeable. In order to overcome this objection in the 50 present instance, means are provided not only for excluding wax particles from the motor chamber but also for efficiently ventilating 55 and cooling said motor. As will be clear from Figs. 3, 4, and 6, the driving shaft 34 of the motor 26 is provided on the end opposite to that carrying the driving pulley 35, with a fan 40 and the side walls of the 60 housing 10 are provided with suitable ventilating openings 41 through which cool air may be drawn and discharged by the action of the said fan 40 thereby effectively dissipating the heat necessarily generated during 65 the operation of the motor. The dis-

sipation of this heat naturally will prevent the melting of any wax particles which may be deposited anywhere upon the housing 10 and it therefore results that the cleaning operations above mentioned need not be performed as frequently with the present machines as is the case with the prior machines.

A portion of the air blast from the fan 40 will also be discharged through the opening 25, thereby further preventing the entry of foreign matter into the motor chamber through said opening.

In order to afford access to the motor chamber 24, a removable bottom plate 42 is provided which is normally held in position by suitable screws or other fastening means 43 engaging the ears 44.

For manipulating the machine, handle 45 is provided, which may be similar to the well known vacuum sweeper handle and which carries the conducting wires 46 for supplying current to the motor 26. The said handle may be provided with a control switch 47 and with suitable clips or brackets 48 upon which the electric cable may be wound when not in use.

It will thus be seen that the present invention provides a floor waxing and polishing machine wherein the motor is mounted in an isolated chamber where it is effectively protected from dust and wax particles and that means are provided for ventilating and cooling this chamber to the end that the heat generated by the operation of the motor will not melt the wax and cause the formation of a coating of wax upon the housing. It will also be clear that owing to the peculiar construction whereby one end of the brush 18 is brought into close proximity with the side wall of the offset 12 that the machine may be effectively employed in polishing substantially the entire surface of the floor including those portions immediately adjacent the vertical walls and which could not be reached with the prior machines.

While one form of the invention has been thus illustrated and described, it is obvious that those skilled in the art may vary the details of construction as well as the precise arrangements of parts without departing from the spirit of the invention and therefore it is not wished to be limited to the above except as may be required by the claims.

What is claimed is:

1. A machine of the class described, comprising a housing having a transverse partition wall dividing it into a brush chamber and a motor chamber, said wall having an opening therein; a brush mounted in said brush chamber; a motor mounted in said motor chamber; driving connections between said motor brush passing through said opening; and a second partition wall disposed at an angle to said first wall and extending into

said brush chamber, adjacent one end of said brush, said second wall being cut away to conform substantially to the periphery of the brush drum, for preventing foreign matter from passing to said motor chamber through said opening.

2. A machine of the class described, comprising a housing having a transverse partition wall dividing it into a brush chamber and a motor chamber, said wall having an opening therein; a brush mounted in said brush chamber; a motor mounted in said motor chamber; driving connections between said motor and brush, passing through said opening; a second partition wall extending forwardly from said transverse wall into said brush chamber, coacting with said brush to prevent foreign matter from passing through said opening into said motor chamber; and a fan in said motor chamber driven by said motor, adapted to force air through said opening into said brush chamber, and thereby also prevent foreign matter from passing through said opening into said motor chamber.

3. A machine of the class described, comprising a housing having a partition wall dividing it into a brush chamber and a motor chamber, said wall having an opening therein; a brush mounted in said brush chamber; a motor mounted in said motor chamber; driving connections between said motor and brush passing through said opening; and a fan in said motor chamber adapted to force air through said opening into said brush chamber.

In testimony whereof I affix my signature.
JOSEPH SASSANO.
